[57] ABSTRACT

Compounds of the formula

wherein R_4 is

wherein m and n are integers between 0 and 3 inclusive provided that $m + n$ is not less than 1 nor greater than 3 or

are prepared by contacting compounds of the formula

where R_2 is allyl, benzyl or tert-butyl, with an acid. These secondary amines find use as plasticizers and additives in explosive compositions.

**AMIDES OF 2-FLUORO-2,2-DINITROETHYL
AMINES**

BACKGROUND OF THE INVENTION

This invention relates generally to chemical compounds and more particularly to amine derivatives which find use as plasticizers and/or additives in explosive compositions, and to a method for the preparation thereof.

As is well known in the art, it is desirable for an explosive composition to have as great an energy release on detonation per unit of weight as is possible so as to maximize efficiency. In order to achieve this result, it is often necessary to include energetic additives in the composition. However, the fact that a compound is highly energetic and can act as an explosive is not sufficient to enable one to use it as an additive in an explosive composition because it must also be thermally stable so that it will not decompose when exposed to moderate or high temperatures and must additionally be compatible with the other constituents of the explosive composition. Thus, continuing research in the explosive composition art is conducted to find materials which can be used as additives to explosive compositions.

SUMMARY OF THE INVENTION

Accordingly, one object of this invention is to provide highly energetic organic compounds.

Another object of this invention is to provide organic compounds that can be used as explosives.

A further object of this invention is to provide organic compounds that can be used as additives in explosive compositions.

A still further object of this invention is to provide organic compounds which are relatively thermally stable.

A further object of this invention is to provide organic compounds which are compatible with the other constituents used in explosive compositions.

A still further object of this invention is to provide a method for the preparation of these organic compounds.

Accordingly, these and other objects of this invention are accomplished by providing compounds of the formula

wherein R_4 is selected from the group consisting of

wherein m and n are integers between 0 and 3 inclusive provided that $m + n$ is not less than 1 nor greater than 3, and

which compounds are prepared by contacting compounds of the formula

wherein R_2 is selected from the group consisting of allyl, benzyl and tert-butyl or any other functional group capable of carbonium ion formation, with an acid.

DESCRIPTION OF THE PREFERRED EMBODIMENT

25 The compounds of this invention represented by the formula

35 are readily prepared by contacting chemical intermediates of the formula

40 with an acid. R_2 represents a substituent which can be easily removed, generally via a carbonium ion intermediate, by treatment with acid. Although R_2 can represent any of the commonly known groups that form a carbonium ion, the preferred values of R_2 are tert-butyl, benzyl and allyl. The strength of the acid employed to effect the desired reaction is important in determining the rate. Thus the stronger acids will effect conversion more rapidly than weaker acids. Preferred acids include protic acids such as sulfuric or trifluoroacetic as well as Lewis acids such as BF_3 or SnCl_4 . When an aprotic acid is used however it is necessary to hydrolyze the reaction mixture to obtain the desired product.

45 Similarly, although temperature is not a critical feature of this process, it will be recognized by those skilled in the art that generally the higher the temperature the faster the reaction rate.

50 The chemical intermediates of this invention of the formula

are prepared by a number of different methods. Where R_4 is

in the above formula, one merely reacts fluorodinitromethane with a compound of the formula $\text{R}_2 - \text{N}(\text{CH}_2\text{OR}_5)_2$ where R_5 is lower alkyl, according to the procedure outlined in Patent application entitled "CHEMICAL" by William H. Gilligan, Ser. No. 110,628, filed on the same date herewith. One can also obtain these intermediate compounds by reacting an amine of the formula

with the appropriate acyl halide, acid anhydride or aromatic halogen of the formula

Similarly the starting materials used to prepare the chemical intermediate of formula I above are likewise prepared from the various prior art techniques such as, for example, contacting 2-fluoro-2,2-dinitroethanol with allyl amine, benzyl amine or t-butyl amine to affect nucleophilic substitution.

It is to be understood within the meaning of this invention that the various R 's used in the formulas herein designate specific groups. Thus whenever R is depicted it represents

while R_2 represents a radical capable of forming a carbonium ion, R_3 represents

and R_4 represents

The general nature of the invention have been set forth, the following examples are presented as specific illustrations thereof. It will be understood that the invention is not limited to these specific examples but is susceptible to various modifications that will be recognized by one of ordinary skill in the art.

EXAMPLE 1
BIS(2-FLUORO-2,2-DINITROETHYL)AMINE

A. About 8.1g crude N,N -bis(2-fluoro-2,2-dinitroethyl) tert-butyamine, the preparation of which is disclosed in Patent application entitled "CHEMICAL" by William H. Gilligan, Ser. No. 110,628 filed on the same date herewith, was added to 30 ml conc. sulfuric acid with stirring and cooling. After 2 hours at ambient temperature, the solution was poured on ice and the crude product recrystallized from methylene chloride-chloroform to give the desired product, m.p. 44°-45°C.

B. A solution of 4.0g of N,N -bis(2-fluoro-2,2-dinitroethyl) benzylamine, the preparation of which is disclosed in Patent application entitled "CHEMICAL" by William H. Gilligan Ser. No. 110,628 filed on the same date herewith, was dissolved in 10 ml of trifluoroacetic acid and warmed to 60°C. After adding 1 ml of concentrated sulfuric acid, the solution was allowed to cool to ambient temperature and stirred overnight. It was then poured on ice and the crude product purified as above in A to yield 2.8g of the desired product.

C. A solution of 2.42g N,N -bis(2-fluoro-2,2-dinitroethyl) benzylamine and 0.44 ml of TiCl_4 in 3 ml carbon tetrachloride was heated at 75°C for 2 days. The solution was cooled, diluted with methylene chloride, washed with dilute hydrochloric acid, dried and filtered. The solvent was evaporated in vacuo to give 1.6g of product.

EXAMPLE 2

N,N'-BIS(2-FLUORO-2,2-DINITROETHYL)OXAMIDE

About 16.8g of tert-butyl 2-fluoro-2,2-dinitroethylamine was dissolved in 50 ml of methylene chloride and cooled to 5°-10°C. About 2.6g oxalyl chloride in 10 ml methylene chloride was then added and the mixture was stirred for 1 hour at room temperature. Following this reaction mixture was heated to reflux for 6 hours and poured into dilute sulfuric acid. The organic solvent was allowed to evaporate and then the residue was filtered giving 8.7g crude N,N'-ditert-butyl-N,N'-bis(2-fluoro-2,2-dinitroethyl) oxamide, m.p. 159°-160°C. About 10g of this product was added to 18 ml acetic acid and 12 ml conc. sulfuric acid and stirred for 2 hours. After ice and water were added, the mixture was filtered to give the desired product which was then recrystallized from acetic acid; m.p. 224°C (dec.).

EXAMPLE 3
N-(2-FLUORO-2,2-DINITROETHYL) FORMAMIDE10.5g tert-butyl 2-fluoro-2,2-dinitroethylamine was dissolved in 30 ml formic acid and 30 ml acetic anhydride was added. The mixture was stirred over night, drowned in water and filtered thereby obtaining 8.5g tert-butyl 2-fluoro-2,2-dinitroethyl formamide. About 9g of this material was added to 15 ml concentrated sulfuric acid and the mixture was stirred for about 6 hours at 25°-30°C. Thereafter the mixture was poured onto crushed ice and diluted to 125 ml with water. Charcoal was added and the solution was then filtered.

It was then saturated with sodium sulfate, extracted 5 times with 50 ml portions of ether, dried and the solvent was then stripped. About 5 g of crude 2-fluoro-

2,2-dinitroethylformamide was obtained. The crude product was degassed and distilled in a molecular still at 0.1 mm/80°-90°C to give the pure product.

EXAMPLE 4
N-(2-FLUORO-2,2-DINITROETHYL)PICRAMIDEA solution of 4.0g allyl fluorodinitroethylamine and 2.5g picryl chloride in 20 ml acetonitrile was heated to 70°C for 24 hours and poured into dilute sulfuric acid. The drowning mixture was extracted with methylene chloride and the extracts were dried and freed from solvent. TLC analysis indicated the product to be a mixture of unreacted picryl chloride and N-allyl-N-(2-fluoro-2,2-dinitroethyl) picramide. The two components were separated by chromatography on silica with methylene chloride as eluant. About 2.5g of product, free of starting material, was obtained. This product was stirred with concentrated sulfuric acid at ambient temperature for 24 hours and the entire mixture was then drowned on crushed ice. Upon recrystallizing from methylene chloride-hexane, 1.78g of N-(2-fluoro-2,2-dinitroethyl)picramide, m.p. 136°-7°C, was obtained.

In a similar manner whenever the other compounds or reactions herein described are desired, one only need follow the above procedures except that the appropriate starting materials should be substituted for the materials hereinbefore used.

Obviously, numerous modifications and variations of the present invention are possible in light of the above teachings. It is therefore to be understood that within the scope of the appended claims the invention may be practiced otherwise than as specifically described herein.

What is claimed as new and desired to be secured by Letters Patent of the United States is:

1. Compounds of the formula

wherein R is selected from the group consisting of

wherein m and n are intergers between 0 and 3 inclusive provided that m + n is not less than 1 nor more than 3.

2. The compound of claim 1 which is N-(2-fluoro-2,2-dinitroethyl) formamide.

3. The compound of claim 1 which is N-(2-fluoro-2,2-dinitroethyl) picramide.

4. Compounds of the formula

wherein R₃ is selected from the group consisting of

wherein m and n are intergers between 0 and 3 inclusive provided that m + n is not less than 1 nor more than 3, and R₂ is a group capable of forming a carbonium ion.

5. A compound according to claim 4 wherein R₂ is selected from the group consisting of t-butyl, benzyl and allyl.

6. A compound according to claim 5 wherein R₃ is

and R₂ is t-butyl.

7. A compound according to claim 5 wherein R₃ is

and R₂ is t-butyl.

8. A compound according to claim 5 wherein R₃ is

and R₂ is allyl.

9. The process of preparing compounds of the formula

wherein R₄ is selected from the group consisting of

9

where m and n are integers between 0 and 3 provided that $m + n$ is not less than 1 nor more than 3 comprising contacting a compound of the formula

wherein R_2 is a group capable of forming a carbonium ion, with an acid provided that when an aprotic acid is used water is added to the reaction mixture.

10. The process of claim 9 wherein R_2 is selected from the group consisting of allyl, benzyl and t-butyl.

11. The process of claim 9 wherein the acid is selected from the group consisting of aprotic acids.

12. The process of claim 9 wherein the acid is a protic acid.
